OR D 10,994

No. 10,994

JAN 28, 1879

UNITED STATES PATENT OFFICE.

CHRISTIAN HERTER, OF NEW YORK, N. Y.

DESIGN FOR WALL-PAPER.

Specification forming part of Design No. **10,994**, dated January 28, 1879; application filed December 23, 1878.
[Term of patent 3½ years.]

To all whom it may concern:

Be it known that I, CHRISTIAN HERTER, of the city, county, and State of New York, have invented a new and original Design for Wall-Paper, of which the following is a full, clear, and exact description, reference being had to the accompanying photographic illustration, making part of this specification, and in which—

A is a series of fan-shaped figures, in the nature of peacock-feathers, which are arranged in rows, the fans of one row overlapping those of the next adjoining row, and so on. The fans or feathers are arranged with irregular

patterns, by which a lighter and more variegated appearance is imparted to the design.

What I claim as new, and desire to secure by Letters Patent, is—

The design for a wall-paper, composed of rows of overlapping fan-shaped figures, as shown and described.

In testimony that I claim the foregoing as my invention I have signed it this 19th day of December, 1878.

CHRISTIAN HERTER.
